United States Patent Office

Des. 193,486

Patented Aug. 28, 1962

193,486

COMBINED HOE, RAKE AND EDGER

Richard Wenger, 212 N. Federal Highway, Dania, Fla.

Filed Mar. 5, 1962, Ser. No. 69,098

Term of patent 14 years

(Cl. D39—1)

FIG. 1

The dominant features of my design reside in the full line portions of the drawing.

I claim:

The ornamental design for a combined hoe, rake and edger, as shown and described.
